REFRIGERATOR CAR

Kurt E. Zeidler, Pittsburgh, Pa., assignor to
Standard Railway Devices Company, a corpora-
tion of Delaware

Application April 14, 1939, Serial No. 267,789

10 Claims. (Cl. 62—17)

This invention relates to refrigerator cars used to transport perishable commodities at a predetermined temperature. The essential features of a refrigerator car are an insulated body to prevent or retard ingress of heat during warm weather and egress of heat during cold weather and a cooling or heating means depending upon the prevailing outside temperature.

This invention applies particularly to cars in which the cooling means, preferably containers for water ice, eutectic ice, brine or dry ice, are suspended immediately below the ceiling of the car. The lading is supported in spaced relation to the floor by a foraminous rack. Flues, preferably associated with the side walls of the car, communicate between the refrigerant compartment and the space under the floor rack to provide a path for the circulation of air. The path is from the refrigerant compartment downwardly through the aforementioned flues, through the space under the floor rack, and upwardly through the lading compartment to the refrigerant compartment.

An object of the invention is to provide as a cooling means refrigerant bunkers having a greater effective cooling surface than those heretofore used. The extent to which air may be refrigerated depends upon the area of cold surface exposed to the circulating air. By providing an ice bunker comprising a container and a subjacent pan with a space therebetween, I have formed an additional air flue not found in conventional bunkers and have therefore increased the refrigerating efficiency.

Another object of the invention is to refrigerate the air by causing it to flow through the drippings of melted refrigerant. I have provided a container, a subjacent pan and means to direct the overflow from the container into the pan. The invention also includes means to direct the circulating air through the above mentioned overflow, thus providing additional refrigeration. It is a further object to humidify the air. It has been found that certain types of fresh fruits and vegetables are preserved in better condition if the air contains a large percentage of moisture. Therefore, I intend that the above-mentioned overflow should also humidify the air.

Other objects and advantages of my invention will be apparent from the following detailed description by referring to the accompanying drawings in which:

Fig. 1 is a partial transverse section of a refrigerator car embodying my invention.

Fig. 2 is a view similar to Fig. 1 showing a modified construction.

Figs. 3 and 4 are longitudinal sections on lines 3—3 and 4—4 of Figs. 1 and 2 respectively.

5 My invention is shown embodied in a refrigerator car having an insulated roof 2, wall 3 and floor 4. The refrigerant bunker is indicated generally by 5 and a hatch 6 is provided in the roof 2 for loading refrigerant into the bunker 5. 10 A floor rack 7 supports a lading in the lading compartment 8 and provides a space 9 between the lading and the floor 4. A flue 10 associated with the wall 3 conducts air which has been refrigerated by the bunker 5 to the space 9 from 15 where it is distributed to the lading compartment 8 through the floor rack 7 which is foraminous for the purpose. The flue 10 also provides a drain for melted refrigerant to the gutter 12 from where it is drained to the outside of the car by any suitable means.

20 In the modification shown in Figs. 1 and 3, the bunker 5 comprises a container 20, pan 21 and partition 22. The container 20 is preferably formed with foraminous upper walls 23 and a 25 liquid retaining lower portion 24. The bottoms of the lower portion 24 and pan 21 are preferably provided with corrugations 25 to increase the strength and rigidity thereof. The lower portion 24 of the container 20 is provided with 30 openings 28 surrounded by upstanding walls 29, the tops of the walls 29 preferably being substantially level with the bottom edges of the lowermost apertures 30 in the upper walls 23 of the container 20 so that a liquid in said container will overflow through both the openings 28 and apertures 30.

35 The pan 21 and partition 22, as shown in Figs. 1 and 3, are rigidly secured together, as by the nailing strips 34 and clips 35. The partition 22 is hinged to the wall 3 at 36 and the pan 21 is 40 releasably secured by the clamp 37 to the upstanding member 39 which is rigidly and permanently secured to the car structure. The lower portion 24 of the container 20 and the pan 21 are each provided with a means for draining, 45 said means being adapted to retain liquid in the lower portion 24 and pan 21 when desired. The means shown comprises a pipe elbow 41 secured to the lower portion 24 by the swivel connection 50 42 so that the leg 43 may be rotated to a depending position for draining of liquid. Springs 44 may be provided to hold the legs 43 in an upstanding position.

55 The containers 20 are preferably spaced apart as shown in Fig. 3 to provide the passages 46 for

air circulation. The pans 21 preferably have portions 47 which underly the passages 46 and are provided with inclined baffles 51 which direct overflow from the apertures 30 into the pans 21. The member 39 is preferably continuous longitudinally of the car and spaced from the container 20 to form the duct 48 and from the roof 2 to form an opening 49. Air circulates upwardly from the lading space as shown by the arrows 50 and follows one of three available paths to the flue 10. The air may circulate through the apertures 30 and through the upper portion of the container 20, being cooled by the refrigerant therein. Other portions of the air circulate through the opening 49 and duct 48 to 15 the space 52 between the container 20 and pan 21, being cooled by contact with the under side of the container 20 and with the liquid or refrigerant in the pan 21. The air flowing through the space 52 is also cooled and humidified by overflow from the openings 28 or apertures 30. Still other portions of the air may flow through the duct 54 between the partition 22 and pan 21, being cooled by contact with the under side of 20 the pan 21.

In the modification shown in Figs. 2 and 4, the pan 64 is secured to the container 20 by the brackets 65, 66. The partition 22 is hinged to the wall 3 at 68 and is latched 69 to a bracket 70 secured to the under side of the pan 64. As 30 shown in Fig. 4, the adjacent ends of the pans 64 are spaced apart to allow passages 72 therebetween for air circulation. The partition 22 is intended to function as a drip pan if required to drain overflow from the container 20 and pan 64 to the flue 10.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

1. In a refrigerator having a roof and a wall, the combination of refrigerating means near said roof and a flue associated with said wall to conduct air from said means to the lower part of the car, said means comprising a container having a liquid retaining lower portion, a pan spaced below said container to provide a space therebetween, a partition spaced below said pan to provide a duct therebetween, and means to overflow a liquid from said lower portion to said pan, the elements being arranged so that air is refrigerated upon flowing through said duct.

2. In a refrigerator having a roof and a wall, the combination of refrigerating means near said roof and a flue associated with said wall to conduct air from said means to the lower part of the car, said means comprising a container having a foraminous upper portion and a liquid retaining lower portion, a pan spaced below said container to provide a space therebetween, a partition spaced below said pan to provide a duct therebetween, and means to overflow a liquid from said lower portion to said pan, the elements being arranged so that air is refrigerated upon flowing

through said space, said duct and said upper portion.

3. A structure as defined in claim 1 wherein a plurality of said containers are spaced apart to provide passages for air circulation and a plurality of said pans have contacting edges to retain liquid overflowing the edges of said containers.

4. A structure as defined in claim 1 wherein said pan and said partition are rigidly secured together and hinged to said wall.

5. A structure as defined in claim 1 wherein said pan is suspended by brackets from said container.

6. In a refrigerator, a refrigerant bunker comprising a container element, a subjacent pan element with a space thereabove for air circulation, means to drain a liquid from said container element to said pan element and a partition element spaced below said pan element to form a duct for air circulation, said elements being arranged to direct circulating air through said space in contact with the liquid in said pan element and also through said duct.

7. In a refrigerator, a refrigerant bunker comprising a container having a liquid retaining lower portion, a subjacent liquid retaining pan with a space thereabove for air circulation, means to overflow a liquid from said lower portion to said pan, said means comprising an aperture in a container wall, said pan extending outwardly beyond the plane of said wall to catch the overflowing liquid, and means to direct a flow of air through said space in contact with the liquid in said pan.

8. In a refrigerator, a refrigerant bunker comprising a container element arranged to retain a mixture of solid and melted refrigerant, a subjacent liquid retaining pan element with a space thereabove for air circulation, means to overflow part of said melted refrigerant from said container element to said pan element, a partition element spaced below said pan element to form a duct therebetween, said elements being arranged to direct circulating air through said space and said duct.

9. In a refrigerator car, a refrigerant bunker comprising spaced apart upper and lower portions, means to overflow a refrigerant from said upper to said lower portion, and means cooperating with said bunker to form an air duct adjacent the lower part of said lower portion, said bunker and last mentioned means being arranged so that circulating air flows between the upper and lower portions of said bunker and also flows through said duct in contact with the lower portion of the bunker.

10. In a refrigerator car, a refrigerant bunker comprising spaced apart upper and lower portions, each adapted to retain a refrigerant, and means cooperating with said bunker to form an air duct adjacent the lower part of said lower portion, said bunker and means being arranged so that circulating air flows between the upper and lower portions of said bunker and also flows through said duct in contact with the lower portion of the bunker.

KURT E. ZEIDLER.
